Primary Examiner — Susan Moon Lee(74) *Attorney, Agent, or Firm* — Polsinelli PC(51) **LOC (10) Cl.** ..... **30-03****CLAIM**(52) **U.S. Cl.**

The ornamental design for a seed reservoir bottle for a wild bird feeder, as shown and described.

DESCRIPTION(53) **Field of Classification Search**

FIG. 1 is a perspective view of the seed reservoir bottle for a wild bird feeder showing our new design.

USPC D30/121, 124, 126–129, 133, 199,

FIG. 2 is an isometric view of the seed reservoir bottle for a wild bird feeder.

D30/110–112, 123, 125; 119/52.2, 51.5,

FIG. 3 is a front view of the seed reservoir bottle for a wild bird, the back view being a substantial mirror image thereof.

119/61.5, 57.8, 57.9, 52.3, 61.1, 531, 63,

FIG. 4 is a side view of the seed reservoir bottle for a wild bird feeder.

119/428–435, 52.4, 55, 61.3, 69.5, 75, 76;

FIG. 5 is a bottom perspective view of the seed reservoir bottle for a wild bird feeder.

47/67, 83; 248/318; D11/164, 152;

FIG. 6 is a top plan view of the seed reservoir bottle for a wild bird feeder; and,

211/128.1; D27/123; D6/495, 460,

FIG. 7 is a bottom plan view of the seed reservoir bottle for a wild bird feeder.

D6/461, 476, 405
